FURNACE

Elmer W. Dany, Brecksville, and Paul S. Gruber, Cleveland, Ohio, assignors to Ferro Enamel Corporation, Cleveland, Ohio, a corporation of Ohio

Application December 24, 1941, Serial No. 424,228

7 Claims. (Cl. 263—42)

This invention relates to furnace construction, and more particularly to certain improvements in fuel-fired, muffle furnaces of the type commonly used in porcelain enameling on metal and in numerous other heating operations where ware is conveyed through a furnace in a more or less continuous manner.

Although the furnace illustrated and described herein is particularly adapted for porcelain enameling, it will be understood by those skilled in the art that the features disclosed herein are readily adaptable to furnaces intended for annealing or other heat treating operations. A very efficient and successful form of continuous furnace is the so-called U-type in which the furnace structure is open at one end and closed at the other end and means are provided for transporting ware into and out of the furnace in a U-shaped path. In this form of furnace the heating zone is disposed at the closed end of the U, and the cold incoming ware enters the open end of the furnace and moves close to, but in the opposite direction from, the heated outgoing ware. Thus the entering ware is preheated by the heat given off from the outgoing ware. Furnaces of the type referred to herein have been heated by electrical heating means, by radiant tubes disposed along the walls of the furnace, and by muffles, in which fuel such as gas or oil is burned, disposed along the walls of the heating zone of the furnace. My present invention relates to improvements in muffle furnaces as distinguished from the electrically heated or radiant tube heated types of furnace.

In prior muffle furnaces with which we are familiar the heating or burning section has been heated by muffle chambers disposed in the floor and side walls of the furnace. The entire heating zone has been open from one side wall muffle to the other and the heat input capacity has been limited by the area of the bottom and side walls of the heating section. Our present invention contemplates the provision of a heated muffle dividing wall, preferably centrally arranged between the side walls of the heating section and extending part or all of the distance between the floor and roof of the heating section. We are aware that U-type furnaces of the electrically heated and radiant tube heated classes have been proposed in which a dividing wall, which supports heating elements, is installed in the closed end of the furnace. The present invention, however, possesses certain definite advantages over such electrically or radiant tube heated structures as will appear more fully later.

It is an object of our present invention to provide a fuel-fired furnace of the type described having a relatively large heating capacity for a given furnace volume. Other objects of my invention include: the provision of a U-type furnace of the muffle type having means for automatically supplying the greatest amount of heat to the ware as it enters the heating section of the furnace and a lesser amount of heat to the ware as it leaves the heating section; the provision of a U-type furnace having a heated intermediate wall in the heating section; the provision of a centrally disposed muffle in the heating section of a fuel-fired furnace together with effective means for conveying products of combustion to said center muffle and from said center muffle in heat exchanging relationship to ware entering the furnace; the provision of a furnace having side muffles and a center wall muffle; and means for controlling the relative proportion of heating effected by the various muffles; the provision, in a cross-fired muffle type furnace having a heated center wall, of means for independently controlling the flow of heated gases through the center wall portion; the provision of improved means for regulating the heat distribution in a muffle type furnace; and the provision of an extremely simple, rugged, efficient, high capacity heating furnace of the type described.

The above and other objects of my invention will appear from the following description of one embodiment thereof, reference being had to the accompanying drawings in which—

Figure 1 is an illustrative horizontal cross-sectional view of a U-type furnace incorporating my improvements, the central portion of the preheating and cooling zone of the furnace being broken away for purposes of more compact illustration. Figure 1 is taken on line 1—1 of Figure 2.

Figure 2 is a vertical longitudinal sectional view taken on line 2—2 of Figure 1.

Figure 3 is a vertical cross sectional view taken on line 3—3 of Figure 1.

Figure 4 is a fragmentary vertical cross sectional view taken on line 4—4 of Figure 1 and illustrating the gas passages at the exit end of the center wall muffle.

Figure 5 is a vertical longitudinal sectional view taken on line 5—5 of Figure 1.

Figure 6 is a vertical cross sectional view taken on line 6—6 of Figure 1.

Figure 7 is a vertical cross sectional view showing the damper controls of the flue outlets, taken on line 7—7 of Figure 1.

The furnace which we have illustrated in the

drawings is of the U-type and has a cross-fired heating zone. However, we do not wish to limit our invention either to a cross-fired furnace or to a U-type furnace as various features of our improved construction are readily adaptable to other furnace designs. In Figure 1 the heating section or zone of the furnace extends from the closed end wall 1 to the end walls 2 of the side muffles. The side walls of the preheating and cooling section of the furnace are indicated at 3 and 4, and, as is best seen in Figs. 2 and 3, the roof 5 of the furnace is provided with a continuous U-shaped slot 6 through which ware supporting bars extend. The path of this slot is indicated in Figure 1 by a dot and dash line 7, and the conveyor members and bars are not illustrated because they are well understood and form no part of the present invention. It will suffice to point out that the supporting elements which extend through the slot 6 and carry the ware are preferably mounted on an endless chain which goes in the direction of the arrow in Figure 1. Ware is loaded onto the conveyor at the open end (the right hand end in Figure 1) of the furnace, and moves into the heating zone where it turns through an angle of 180° and then passes on out in closely spaced relation to the incoming ware. As the heating and cooling zone is preferably open across its entire width, a free transfer of heat from the hot outgoing ware to the cold incoming ware is obtained.

The cross-fired heating arrangement which we have illustrated includes four burners 8 located on one side of the furnace below the level of the floor 9 thereof, and three burners 10 located on the opposite side of the furnace and in staggered or offset relation to the burners 8. Each of the burners 8 directs its flame and products of combustion into a transversely extending tunnel 11 below the floor 9 of the burning section of the furnace, and each of the burners 10 directs its flame and products of combustion into a transversely extending tunnel 12, also located below the floor 9 of the furnace. These tunnels are separated by transverse walls 13 which extend across the bottom of the heating section of the furnace and also form supports for the refractory floor plates forming the floor 9 of the furnace heating section.

As may be clearly seen in Figure 3, the products of combustion from each burner 8 pass through the corresponding tunnel 11 below the furnace floor 9, and then move upwardly into the side muffle chamber 14 through an open passage 15 at the end of the tunnel 11. Products of combustion from the burner 8 shown in Figure 3 cannot enter the side muffle 16, however, because of the baffle member 17 which shuts off communication between the tunnel 11 and the side muffle 16.

The muffles 14 and 16 preferably extend along the full length of the side walls of the heating chamber, and are provided with inner, relatively thin, refractory walls 14a and 16a. In each of the muffles 14 and 16 we preferably provide vertically extending pilasters for assisting in the desired distribution of heat through the muffles. In muffle 14 these pilasters are seen at 18, 19 and 19a, the pilaster 18 extending up relatively close to the top of the muffle chamber, and the pilasters 19 and 19a being of successively decreasing height. Similar pilasters 20, 21 and 22 are disposed in the side muffle 16. As will appear later, the flow of gases through the side muffles 14 and 16 is from the closed end of the furnace toward the open end (left to right in Figs. 1 and 2), and

the pilasters just referred to assist in maintaining this flow in the desired manner whereby more uniform heating of the walls 14a and 16a is obtained.

5 The intermediate or center wall muffle is generally indicated at C, and comprises side walls 23 and 24, end walls 25 and 26, and a top portion 27. The side walls 23 and 24 are supported on suitable base blocks 28 and 29 which span the transverse walls 13 and are supported thereby. The wall C has its left hand end (Fig. 2) spaced from the closed end 1 of the burning chamber and extends to a point approximately even with or extending beyond the other end of the burning chamber. The top 27 of muffle C lies below the roof 5, and thus the area of the top 27 is effective for heat radiation. In some instances, however, it may be desirable to extend the side walls of the center muffle up to the ceiling or roof 20 of the furnace. So also, although muffle C is illustrated as located midway between the side wall muffles, it may be located in any position between the side walls of the furnace.

25 The interior of the center muffle C communicates with the transverse tunnels 11 and 12, which it overlies, by means of the openings 30. We preferably install pilasters 31, 32, 33, 34 and 35 in the muffle C. These pilasters are supported on the walls 13, and are stepped down, as seen in Figure 2, from the highest pilaster 31 to the lowest pilaster 35 adjacent the exit end of the center muffle.

30 Products of combustion from the tunnels 11 and 12, over which the muffle C is disposed, may pass upwardly into the muffle C through the passages 30. Pilasters 31, 32, 33, 34 and 35 cause the products of combustion to sweep over the entire inner area of the muffle C and assist in effecting even heating of the walls of the muffle. As 35 the products of combustion approach the end wall 25 they are directed downwardly by this wall and pass out the muffle wall C through the outlet opening 36 which, as is best seen in Figure 4, opens into the end portion of a duct 37 which in turn extends longitudinally beneath the floor 38 of the preheating and cooling chamber.

35 The products of combustion which enter the side muffles 14 and 16 move toward the open end of the furnace and pass downwardly through openings 39 and 40 (Fig. 1) into the end portions of ducts 41 and 42, which also extend beneath the floor 38 of the preheating and cooling section. The ducts 37, 41 and 42 preferably extend substantially the full length of the preheating and cooling section of the furnace and when they approach the open end of the furnace they are turned at right angles, as clearly seen in Figure 1, and connect with the stack 43 located at one side of the furnace. Independently adjustable dampers 44, 45 and 46 are provided for the flues 37, 41 and 42 respectively. By adjusting these dampers the relative sizes of the outlet openings of the flues 37, 41 and 42 may be adjusted, and thus the draft on each of the muffles 14, 16 and C may be regulated.

40 For example, if it is desired to increase the quantity of heat applied to the center muffle C, the damper 44 may be opened without changing the position of the dampers 45 and 46. This will result in a greater proportion of the hot products of combustion from the burners 8 and 10 being drawn up through the inlet openings 30 into the center muffle C. In like manner, if it is desired to apply more heat through the muffle 16 adjacent the incoming ware than through the muffle

14, the relative positions of the dampers 45 and 46 may be adjusted to accomplish the desired result.

This flexibility of control of the muffles is extremely advantageous as it is frequently desirable to vary the heat input to the ware at different parts of the burning zone. My center wall muffle provides a form of automatic means for applying heat to the ware without any complicated controls such as are necessary with electrically heated furnaces. As the unburned ware enters the burning section, heat given off from the wall 24 and from the wall 16a will rapidly raise the temperature of the ware. The resulting cooling effect on the walls 24 will call for more heat from the products of combustion within the muffle C, and thus the temperature will be maintained at the necessary value. As the ware leaves the burning zone and passes between the walls 23 and 14a, however, it has been heated to its desired temperature, and thus there is not as great a flow of heat from the walls 23 and 14a to the ware as there was from the walls 16a and 24. Thus the greatest heat is automatically applied to the incoming ware where it is most desirable.

By adjusting the dampers 44, 45 and 46, as explained above, heat may be applied uniformly to both sides of the ware and the temperature at the various points in the heating zone may be maintained within the desired limits. Furthermore, as all of the products of combustion pass out beneath the floor of the preheat and cooling zone, an efficient heat transfer is obtained which serves to assist in preheating the incoming cold ware. Although we have illustrated the total width of ducts 37, 41 and 42 as extending across substantially the full width of the preheat and cooling section, it will be understood that these ducts may, if desired, be positioned beneath only the portion of floor of the preheat and cooling section over which the cool entering ware passes.

It will further be understood that the structural arrangements of brick, refractory elements, etc., illustrated herein is more or less diagrammatic, and that modifications and variations in the structural features may be made without departing from the precepts of our invention. The features of our center wall or island type muffle and independent control of the heat applied thereto may be taken advantage of in the so-called counter-flow furnaces, or in other types of straight-through furnaces, as distinguished from the U-type of furnace which we have illustrated.

Although we have described the illustrated embodiment of our invention in considerable detail, it will be understood by those skilled in the art that numerous variations and modifications may be made in the form and arrangement of the parts. We do not therefore wish to be limited to the particular furnace structure herein shown and described, but claim as our invention all embodiments thereof coming within the scope of the appended claims.

We claim:

1. In a furnace of the type described, a heating section, transversely extending tunnels beneath the floor of said heating section, burners adapted to direct their products of combustion into said tunnels, muffles in the side walls of said heating section, a center wall muffle disposed between said side wall muffles in said heating section, means for establishing communication between one of said side wall muffles and some of said tunnels and between the other of said side wall muffles

and others of tunnels, means for establishing communication between said center wall muffle and at least certain of each of said tunnels, a preheating section connecting to one end of said heating section, independent ducts extending from said side wall muffles and said center wall muffle in heat transferring relation to said preheating section, stack means providing an outlet for said ducts, and independent means for regulating the flow of gases through each of said ducts.

2. In a U-type furnace having an open end and a closed end, a heating section adjacent said closed end, a preheating and cooling section between said heating section and said open end, wall muffles on opposite sides of said heating section, an intermediate muffle in said heating section between said wall muffles and spaced from said closed end of said furnace, a combustion tunnel extending transversely of said heating section below said muffles, gas conducting connections from said tunnel into one of said wall muffles and into said intermediate muffle, duct means extending below said preheating and cooling section for conducting gases away from said one of said wall muffles and said intermediate muffle, and means for apportioning the flow of gases between said muffles.

3. In a U-type furnace having an open end and a closed end, a heating section adjacent said closed end, a preheating and cooling section between said heating section and said open end, wall muffles on opposite sides of said heating section, an intermediate muffle in said heating section between said wall muffles and spaced from said closed end of said furnace, a combustion tunnel extending transversely of said heating section below said muffles, gas conducting connections from said tunnel into one of said wall muffles and into said intermediate muffle, a second combustion tunnel extending transversely of said heating section below said muffles and communicating with the other of said wall muffles and said intermediate muffle, independent duct means extending below said preheating and cooling section for conducting gases away from said wall muffles and said intermediate muffle, and means for controlling the flow of gases through said muffles.

4. In a fuel fired muffle furnace, a plurality of oppositely and alternately disposed transversely directed burners, transversely disposed combustion tunnels for said burners separated by parallel walls supporting the floor of said furnace, side muffle walls supported at the ends of said tunnel walls defining side muffles communicating with alternate tunnels at the ends opposite said burners respectively, central muffle walls supported on said tunnel walls in the mid-portion of said furnace defining a central muffle communicating with each of said tunnels, exhaust passages leading from said muffles, pilasters of varying heights supported by said tunnel walls disposed in said muffles for distributing the flow of gases from said tunnels to said passages within said muffles, and means for apportioning the flow of said gases between the several muffles.

5. In a fuel fired muffle furnace, a plurality of transversely directed burners, transversely disposed combustion tunnels for said burners separated by load bearing walls, side muffle walls supported at the ends of said tunnel walls defining side muffles communicating with said tunnels at the ends thereof, central muffle walls supported on said tunnel walls in the mid-portion of

said furnace defining a central muffle communicating with said tunnels, exhaust passages leading from said muffles, pilasters supported by said tunnel walls disposed in said muffles for distributing the flow of gases from said tunnels to said passages within said muffles, and means for apportioning the flow of said gases between the several muffles.

6. In a fuel fired muffle furnace, a pair of transversely disposed combustion tunnels, a burner disposed in the end of one of the tunnels and a burner disposed in the opposite end of the other tunnel, side muffles supported above and at the ends of said tunnels and extending transversely thereof, each side muffle communicating with one tunnel at the end opposite the burner, a central muffle disposed above said tunnels and between said side muffles and extending substantially parallel with said side muffles, said central muffle communicating with both said tunnels, exhaust passages leading from each of said muffles sep-

arately, and means for controlling the flow of gases through said exhaust passages whereby to apportion the heat between said muffles.

7. In a fuel fired muffle furnace, a pair of transversely disposed combustion tunnels, burners disposed in the ends of said tunnels, side muffles supported above and at the ends of said tunnels and extending transversely thereof, each side muffle communicating with only one combustion tunnel at one end thereof, a central muffle disposed above said tunnels and between said side muffles and extending substantially parallel with said side muffles, said central muffle communicating with both said combustion tunnels, exhaust passages leading from each of said muffles separately, and means for controlling the flow of gases through each of said exhaust passages independently.
